UNITED STATES PATENT OFFICE.

AUGUSTA P. MCKAY, OF ROME, GEORGIA, ASSIGNOR TO MCKAY DISC PLOW CO., OF ROME, GEORGIA, A CORPORATION OF GEORGIA.

DRAFT APPLIANCE.

1,189,981.

Specification of Letters Patent.

Patented July 4, 1916.

Application filed November 5, 1915. Serial No. 59,834.

To all whom it may concern:

Be it known that I, AUGUSTA P. MCKAY, a citizen of the United States, residing at Rome, in the county of Floyd and State of Georgia, have invented certain new and useful Improvements in Draft Appliances; and I do hereby declare the following to be a full, clear, and exact description of the invention, such as will enable others skilled in the art to which it appertains to make and use the same.

The present invention relates to improvements in draft appliances, and consists more particularly in an improved draft appliance similar in type to that disclosed in my similarly entitled co-pending application Serial No. 38,494, filed July 7, 1915.

It is an object of the present invention to construct and arrange the several parts so as to have the spring-pressed rod disposed substantially parallel to the line of draft, whereby the possibility of the same being moved or tripped by stalks or other passing obstructions will be eliminated.

Another object of the present invention resides in so disposing the parts of the improved appliance as to render it practically impossible for the coupling element or other releasable or yieldable parts to be shaken or jarred to uncoupling position, or to be otherwise accidentally displaced by forces other than the draft strain.

It is a further object of the present invention to simplify the construction of the appliance, and to construct the same to offer as rigid resistance under a reverse strain, when the engine is backed, as when subjected to strain under ordinary forward running conditions.

With these and other objects in view the invention consists in the novel details of construction and combinations of parts more fully hereinafter disclosed and particularly pointed out in the claims.

In the accompanying drawings forming a part of this application; and in which similar reference symbols indicate corresponding parts in the several views: Figure 1 is a top plan view of an improved draft appliance constructed in accordance with the present invention. Fig. 2 is a side elevational view of the same, showing the parts in coupled position; and Fig. 3 is a similar view, partly in section, and illustrating the parts as released.

Referring more particularly to the drawings, the frame of the appliance is composed of a pair of elongated members 1 and 2 arranged parallel and in contact throughout the major portion of their length, and having their forward ends bent apart, as clearly shown in Fig. 1, to provide a slot or socket for receiving a bill 3 on a coupling element 4; which latter is preferably of substantially the same configuration employed in connection with my prior appliance as set forth in the application above.

The forward ends of the members 1 and 2 are connected by a pair of spaced bolts or rivets 5 and 6 between which the bill 3 of the coupling element is adapted to be fitted, and upon the latter bolt 6 of which the same is adapted to revolve, as indicated in Fig. 4, to effect the release of the same. The coupling element 4 is under a constant strain, tending to revolve and release the same, by a connection 7, which may be rigid or flexible, and whereby the coupling element is connected to the traction vehicle.

The coupling element is normally held against such movement by a pin 8 projecting from opposite sides of the same and being fitted in recesses 9, formed one in each of a pair of members 10 and 11 connected together by a bolt or other means 12 to constitute a lever which is fulcrumed, as indicated at 13, on a rivet or bolt, which latter also serves to connect the members 1 and 2 of the frame. The recesses 9 in the members 10 and 11 of the lever are formed with inclined or cam lower walls 14, whereby said lever may be swung from the position shown in Fig. 2 to that shown in Fig. 3, and permit the release of the coupling element 4 when the draft strain exceeds a predetermined degree.

At their upper ends the members 10 and 11 of the lever are connected by a pin 15 engaged by an eye 16 bent from the end of a rod 17; the latter being slidably mounted through an eye bolt 18 fitted between a pair of bulged portions on the frame members 1 and 2, and held for vertical adjustment therein by nuts 19 and 20. The rod 17, at its upper free end, is threaded to receive a pair of lock nuts 21 and 22, and between said lock nuts and the eye bolt 18 is confined a coil spring 23, encircling said rod 17 and normally tending to move the same to the position shown in Fig. 2 and 110

preserve the engagement between the pin 8 on the coupling element 4 and the recesses 9 in the lever members. The frame is connected to the drawn vehicle by loose or flexible connection 24, engaging through a ring 25, or other device, secured through perforations in the rear ends of the frame members 1 and 2. A similar ring member 26 may be interposed between the coupling element 4 and the connection 7, but it is to be understood that I do not wish myself restricted to any particular form of connection, as the same may obviously be of a variety of forms either flexible or rigid.

15 In the operation of the improved appliance the frame, including the members 1 and 2, is coupled by the connections 24 and 25 to the plow, harvester, or other implement to be drawn, and the coupling element 4, through the connections 26 and 7, is coupled to the engine or traction vehicle. The appliance may be reversed, if desired, and the coupling element 4 connected to the drawn implement while the frame is connected to the traction vehicle, the operation of the appliance being the same.

When the drawn vehicle encounters an obstruction placing a sudden and severe strain on the coupling appliance, such as 30 would be likely to cause breakage of the same, such strain exerted through the draft connection 7 and ring 26 will be effective to revolve the coupling element 4 and bill 3 about the bolt 6 as a center, forcing the 35 pin 8 to ride on the inclined or cam lower walls 14 of the recesses 9 in the lever members 10 and 11, and move such lever to the position shown in Fig. 3 in opposition to the action of the coil spring 23 which is 40 simultaneously being compressed between the eye bolt 18 and lock nuts 21, 22. After the release of the pin 8 from the recesses 9, the connection 7 will swing the coupling element 4 to disengage the bolts 5 and 6, 45 and the same will be drawn along with the traction vehicle, leaving the implement uncoupled.

It is obvious that the lock nuts 21, 22, 50 may be adjusted along the rod 17 to place the coil spring 23 under any required pressure to permit release of the coupling appliance under any desired degree of strain, and said rod 17 is disposed horizontally and substantially parallel to the line of 55 draft so as not to be encountered by stalks or other obstacles which would have a tendency to move the connected parts and release the coupling element 4. In such

horizontal position the spring-pressed rod 17 is not subject to be reciprocated by the 60 vertical vibration of the vehicles, and the same is therefore not liable to be shaken or jarred to release the coupling.

It is obvious that those skilled in the art may vary the details of construction and 65 arrangements of parts without departing from the spirit of my invention, and therefore I do not wish to be limited to such features except as may be required by the claims. 70

I claim:

1. An improved draft appliance comprising a frame connected to one vehicle and providing a socket therein, a coupling element having a bill removably fitted in said 75 socket and adapted to swing to release the same, a lever mounted on said frame and provided with a recess therein having a lower inclined face, a pin on said coupling element normally engaging the recess in 80 said lever to hold the former in coupled position, yieldable means for maintaining said lever with the recess engaging said pin, and a connection between said coupling element and the other vehicle for tending 85 to revolve said coupling element and engage the pin with the inclined face of said recess whereby to move the lever in opposition to said yieldable means and release the coupling element, substantially as described. 90

2. In an improved draft appliance of the character described, the combination of a frame connected to one vehicle and comprising a pair of members disposed parallel 95 and in contact, said members being bent apart at one end to provide a socket, a pair of spaced bolts connecting said bent-apart ends, a coupling element, a bill on said coupling element engaging the socket 10 in said frame and fitted to swing between said bolts to release the same, a lever comprising a pair of connected members pivoted on said frame and provided with cam recesses therein, a pin on said coupling element engaging said recesses, yieldable means for holding said lever to maintain the pin in said recesses, and a connection between the other vehicle and said coupling element for tending to revolve the latter 11 to disengage said pin and release the appliance, substantially as described. 10

In testimony whereof, I affix my signature.

AUGUSTA P. MCKAY.
